UNITED STATES PATENT OFFICE

ANTON FAZEKAS, OF SAN FRANCISCO, CALIFORNIA

DESIGN FOR AN ILLUMINATED HOUSE NUMBER PLATE

Application filed February 24, 1932. Serial No. 42,981. Term of patent 14 years.

To all whom it may concern:

Be it known that I, ANTON FAZEKAS, a citizen of the United States, residing at San Francisco, in the county of San Francisco and State of California, have invented a new, original, and ornamental Design for an Illuminated House Number Plate, of which the following is a specification, reference being had to the accompanying one sheet of drawing, forming part thereof.

Figure 1 is a front view of an illuminated house number plate, showing my new design;
Figure 2 is a top view;
Figure 3 is a side view thereof.

I claim:

The ornamental design for an illuminated house number plate as shown.

ANTON FAZEKAS.
